MACHINE FOR TRIMMING THE PRINTING
FACES OF TYPE BARS OR SLUGSJames C. Plastaras, Laurelton, N. Y., assignor to
Mergenthaler Linotype Company, a corporation
of New YorkApplication September 26, 1931
Serial No. 565,230

6 Claims. (Cl. 90—19)

This invention relates to machines for trimming the printing faces of type bars or slugs, such as are cast in the commercial linotype machine.

5 In casting the larger slugs, say, from 42 pt. to 60 pt., spots frequently occur on the printing faces of the slugs, and unless removed, cause corresponding imperfections in the printed matter. Such imperfections are due largely to slight
10 irregularities or unevenness in the bottom surfaces of the matrix cavities in which type characters are cast and, although extreme care and accuracy are observed in the course of matrix manufacture, the degree of perfection attained
15 in punching or forming type producing cavities is governed more or less by variations in the grain of the metal used and is therefore very uncertain. In overcoming the described difficulty, it has heretofore been a common practice
20 to rub by hand the printing faces of the slugs upon an emery coated block before assemblage in the printing forms. This practice, however, requires that each slug be handled and inspected separately, and is slow, tedious, and otherwise
25 objectionable.

The present invention, which dispenses entirely with all such manual operations, is directed to a novel machine for automatically finishing or trimming the printing faces of the slugs
30 produced in the linotype machine. This machine, moreover, is small, compact, and portable and yet thoroughly efficient in operation.

A preferred embodiment of the invention, possessing the above characteristics and capable
35 of trimming the slugs with great precision, comprises a table support for the slugs rotatable at a slow rate of speed, whereby the slugs may be placed upon or removed from the table, while the machine is in full operation. Associated with
40 the rotatable support is a cutter for trimming the slugs and rotatable at a high rate of speed, whereby the slugs are trimmed during one rotation of the table and with a multitude of light cutting strokes, thereby avoiding stress on any
45 of the bearings of the device. The means for rotating the table and cutter, and the motor for driving these parts, are all of such character and so arranged and coordinated that the device is operated without stress or wear of its parts
50 and entirely without chatter, whereby the original alinement of the rotating parts will be preserved and there will always be maintained the constant plane of rotation of the printing faces of the slugs with respect to the cutter which is
55 necessary for a perfect trimming operation.

In the accompanying drawings, the invention is shown merely in preferred form by way of example, but obviously many changes and variations may be made therein which will still be comprised within its spirit. It should therefore be understood that the invention is not limited to any specific form or embodiment, except insofar as such limitations are specified in the claims.

Of the drawings:

Fig. 1 is a perspective view of the complete machine;

Fig. 2 is a longitudinal section taken on the line 2—2 of Fig. 3;

Fig. 3 is a horizontal section taken on the line 70 3—3 of Fig. 2;

Fig. 4 is an enlarged plan view of part of the rotating table for supporting the slugs during the cutting or trimming operation of the cutter head;

Fig. 5 is a detail view of the cutter, partly in section and taken on the line 5—5 of Fig. 4;

Fig. 6 is a perspective view of part of a slug of one form; and

Fig. 7 is a similar view of part of a slug of 80 another form.

Referring to the drawings in detail, and first briefly describing a frame in which the operative parts of the machine are mounted, the preferred embodiment of the invention therein illustrated 85 includes a small compact casing 1 made of cast metal. The casing is hollow for the sake of lightness and so that it may house certain parts of the mechanism.

The base of the casing is oblong and box-like in shape and provided at its corners with legs by which the device may be attached in a conventional manner to a support, as a table; and the base is roughly divided into four compartments by longitudinal and lateral strengthening ribs, 95 all as clearly shown in Figs. 2 and 3. The bottom plate 2 of the enclosed base is formed forwardly with a depending boss 3, which will be later referred to, and the forward part of the base is shallow, see Fig. 2, its cover being a flat top plate 4 removably secured to the base. Rearwardly, the base is higher than in the forward part and a cross wall 6 is arranged above the plate 4, as clearly shown in Figs. 1 and 2. The tops of the surrounding walls of the said rear portion of the base are flanged to receive a hollow standard 7, forming the upper part of the casing, and which standard is removably secured to the base with bolts in a usual way. 105
The hollow standard 7 rises, as stated, from 110

the rear part of the base, and at a suitable height thence bends forwardly to form a hollow arm 8, which extends longitudinally in parallel relation to the flat base plate 4, so as to overlie the same, the distance between the plate 4 and the arm 8 being sufficient to permit the installation and operation, between the said plate and arm, of the trimming mechanism hereinafter described. At its outer end the arm 8 terminates in a boss 9, which will be later considered.

To support the slugs to be trimmed, and in order conveniently to accommodate the largest number of slugs possible within the narrow confines of the compact, portable device, an annular table 11 is provided and given a movement of rotation past a cutter with which the machine is furnished and which will be presently described. In order that the cutting operation may be maintained in a constant plane, the top surface of the table, on which the slugs are secured, is made perfectly level and even, so that all points thereof are in a common plane. Parthenetically, it may be noted that the slugs to be operated upon have already been trimmed on their bottoms.

The invention has in view, also, that the slugs be placed upon the table or taken therefrom while the table is in motion and without interfering with the operation of the machine. Accordingly, the table is arranged with a forced fit upon a rotatable shaft 12, which will be later considered, geared to rotate at a slow rate of speed, say, three revolutions per minute. The slugs 10 are secured to the table 11, as shown in Figs. 1 and 2, by means of oblong abutments 13, preferably four in number and arranged in hollow square formation. These abutments 13 are formed with smooth even sides in perpendicular relation to the flat level surface of the table, and the slugs to be trimmed (specimens 10 of which are shown in Figs. 1 and 2) are pressed firmly against said sides with their heads overhanging the tops of the abutments. The abutments are of such length and height that they will accommodate slugs of any size or character.

The slugs are maintained in position against the abutments 13 by clamps 14, one for each abutment, and which clamps are swivelled in adjacent ends of set screws 16, whose other ends are anchored in studs 17 (see Fig. 2). These studs 17 have screw end pieces and are bolted to the table, passing through orifices 18 formed therein. The table 11 is formed with a number of these orifices 18, at convenient distances apart, as shown in Fig. 1, so that the studs 17 may be supplied in varying number and arrangement. As will be apparent, it is an easy and simple operation to turn a set screw 16 in the proper direction and thus release a clamp 14 from its holding position against the side of the slug 10, and then remove the slug; and, conversely, when the slug has thus been removed, to insert another slug in its place and refasten the clamp 14 in operative or holding position by merely turning the set screw 16 in the opposite direction; and all, as has been stated, without interfering in the least degree with the operation of the machine.

Cutter tools 19 for cutting or trimming the printing faces of the slugs are mounted in a cutter head 20, the location and diameter of the cutter head being such that, as the slugs are carried around by the rotating table, the tops of the type characters, irrespective of size, will

pass through the orbit of the cutter and hence be trimmed thereby, (see Figs. 1 and 4).

And here it may be said that, in practicing this invention, it is preferred, although not at all necessary, that the slugs should be cast of slightly greater than normal type height, thus providing a small excess of metal on the type characters to be trimmed or otherwise removed in obtaining the flawless printing faces desired. This greater-than-type-height of the slugs will not only compensate for the metal removed by the cutters, but will contribute to a more satisfactory performance of the cutters, since a continuous surface of metal on each type character will be presented to the cutters for their action thereon rather than a succession of surfaces made by excrescences or irregularities of the type faces.

It is also preferred, in accordance with another feature of the invention, that the cutter head 20 be rotatably mounted, so that the cutter tools 19 shall operate on the slugs with a multitude of light cutting strokes. The cutter head 20, therefore, is mounted to rotate at very high speed, say, thirty-five hundred revolutions per minute, so that in one rotation of the table the printing faces of any slugs mounted thereon will be trimmed and this without any appreciable strain on the parts or disturbance of their true relative positions.

It is pointed out that, as a slug is carried by the rotating table 11 into the cutting zone, the leading end of the oblong slug will in its turning movement describe an arc of a circle, the following body of the slug also describing a constantly decreasing arc until the slug is moved clear of the cutting zone. The cutter tools 19, also, in being carried around by the cutter head 20, will describe a circle, whose diameter is great enough to define a cutting zone appropriate for the largest slug to be trimmed.

As shown in Figs. 1 and 4, the cutter head 20 is cruciform in shape and the cutter tools 19 are arranged in passages 22 extending through opposite arms 23 and 24 of the cutter head 20 and with the cutting points of the tools protruding therefrom. The passages 22 are formed slantingly in the arms of the cutter head so that the cutter tools 19 will be arranged in angular relation to the slugs 10 and present to the latter only a cutting point rather than an edge. The cutting tools are cylindrical in shape and their longitudinal positions in the passages 22 are defined by screw plugs 19^a. The tools are held against rotary or longitudinal movement in the passages 22 by set screws 19^b, as clearly shown in Fig. 5. At its operative end each tool 19 is cut away to a vertical edge with unequal elliptically shaped side faces 25 and 25^a, said faces preferably forming the complements of each other. A great advantage of this tool is that it can be rotated in its passage in the cross arm on its own fixed longitudinal axis and thus present for a considerable extent, when slightly rotated, a fresh point of the curved edge of the larger elliptical face 25 as a cutting point. Another advantage of the tool is that it can be readily sharpened by honing.

It is to be noted that, as heretofore stated, the flat level table is mounted in such manner as to rotate in a constant plane with reference to the cutters, which also move in a constant plane parallel with the surface of the table, so that the slugs carried past the cutter will present perfectly flat even printing faces as a result of

the trimming operation. Furthermore, the table is so mounted that it can be adjusted toward and from the cutter to vary the depth of cut or to accommodate slugs of different height.

5 To insure perfect rotation, the table 11 is arranged with a forced fit as heretofore stated, upon a vertical shaft 12 which is formed with cone-shaped bearing recesses 27 and 28 in its lower and upper ends, into which ends seat 10 correspondingly cone-shaped bearing ends 29 and 30 of pintles 32, 33. These pintles at their opposite ends are arranged in sockets 34, 35 formed respectively through the bosses 3 and 9, hereinbefore mentioned, the shaft 12 passing 15 through an orifice in the plate 4, all as clearly shown in Fig. 2.

The pindle 33 extends entirely through the socket 35 in the boss 9 and is screw threaded in the upper end of the same as at 36 to facilitate 20 and maintain its adjustment vertically. When the pindle 33 has been adjusted in a desired vertical position, it is locked in such position by a set screw 37 bearing against the pindle through a threaded passage in the side of the boss 9, 25 as shown in Fig. 2. To protect the bearings at the upper end of the shaft 12 from dust and other foreign matter, a tube 38, see Fig. 2, surrounds such bearings and is held in place against the boss 9 by a coil-spring 37^a bearing against the tube 38 and the table 11.

30 The socket 34 in the boss 3 is closed with a screw plug 39, thus permitting access to the pindle 32, when desirable for any purpose; and when the pindle has been adjusted to required position, it is locked in such position by means of a locking screw member 40 which is threaded in the side of the socket 3 and bears at its inner end against the side of the pindle.

This form of rotatable mounting of the table 40 11 is of peculiar advantage in association with the rotatable mounting of the cutter, being in its nature designed to maintain a constant vertical relation between the shaft 12 and the pindles 32 and 33 and, therefore, to maintain 45 a constant plane of rotation of the table, while at the same time the absence of stress or pressure on the cone-shaped bearings of the shaft and its pindles will avoid wear on those parts. The parts also are readily accessible and may 50 be installed, removed and adjusted with ease and facility.

55 While the vertical position of the table 11 and the shaft 12 and, therefore the vertical position of the printing faces of the slugs in relation to the cutting or trimming tools, may be adjusted at will, it is of great advantage that such vertical adjustment can be made with great delicacy, when operating, as in this case, in small dimensions, the amount of metal to be removed from the printing faces of a slug being very slight, often being less than one thousandth of an inch.

In order, therefore, to facilitate the adjustment of the shaft 12 and rotating table 11 to various positions vertically, the boss 3 is formed with three symmetrically disposed wells 41, containing coil springs 42, which at their outer or upper ends surround protuberances 43 of a plate 44, which in turn bears against an annular shoulder 45 on the pindle 32 (see Fig. 2). Upon withdrawing the locking screw 40 from the side of and thus releasing the lower pindle 32, the shaft 12, which rests thereon, will then be upheld by the said springs 42, and its vertical 70 position may be very accurately established,

within the required limits, by vertical adjustment of the upper pindle 33, as will now be apparent. The pindle 32 can then be locked in position by the locking screw 40. It will readily be seen that because of this spring support, 80 adjustment of the finest character of the shaft 12 and consequently the slug supporting table carried thereby can readily be made.

The fine, precise adjustment of the table 11 and the slugs carried thereby is further facilitated by a dial 45^a, calibrated to indicate ten thousandths or other minute divisions of an inch, and which dial is mounted on the pindle 33 by means of a set screw 46 extending through a passage in the dial, as shown in Fig. 2, and contacting with the wall of an annular slot 47 formed in the surface of the pindle 33. A pointer 48 is mounted on the boss 9 and cooperates with the dial 45^a in indicating the vertical position of the table support and the slugs thereon carried.

It is to be observed that the cutter head 20 in its rotation maintains a constant plane parallel to that of the table 11, and as shown in Fig. 2, the cutter head 20 is firmly attached to the lower end of a vertical shaft 49 arranged in the opposite sides of the hollow arm 8; and, where it rotates in bearings in the sides of such arm, it is formed with cone-shaped hub portions 50 and 51, respectively, which fit in correspondingly 100 cone-shaped bearings 52 and 53. The lower bearing 52 is formed in a thimble 52^a supported by the lower side of the hollow arm 8, the thimble having at its upper end a peripheral flange 52^b seated upon an annular shoulder 110 formed around the opening which contains the thimble. The upper bearing 53 is formed in the lower end of a cylindrical member 53^a slidable vertically in a cylindrical chamber of a cap plate 8^a attached to the upper side of the 115 hollow arm 8. The bearing member 53^a has an upper threaded extension 53^b screwed to the cap plate 8^a and locked thereto by a nut 53^c resting upon the plate 8^a, the extension 53^b being hollow and forming an oil reservoir above the 120 head of the shaft 49, which reservoir is closed at the top by a plug 53^d. As thus mounted, the cutter head shaft may be forced downwardly to seat its cone-shaped hub portions 50 and 51 in the corresponding bearings 52 and 53 to take 125 up any play or otherwise to set the cutter head and shaft in their proper positions. As will also be seen, the arrangement is such that the parts may be quickly and easily assembled or disassembled when desired.

In order to rotate the cutter drive shaft 49 at the high speed required, a high speed motor 54 is mounted upon arms 55 of a bracket 56 bolted to the rear of the frame 1, see Figs. 2 and 3. To avoid vibration of the parts, the 135 motor rests upon springs 57 encased in recesses 58 formed in said arms 55. In rotating the shaft 49, a belt 60 runs over a small pulley 61 of the shaft 62 of the motor and thence to and over a larger pulley 63 mounted upon the said 140 driving shaft 49 (see Fig. 2). The comparative sizes of the two said pulleys are regulated to produce the desired high rate of speed of rotation of the cutter head driving shaft 49.

As has been stated, the table 11 is designed 145 to rotate at a very low rate of speed and, as it is desirable to furnish all the operative power for the device from the motor 54, suitable reducing gears are provided between the driving shaft 62 of the motor and the shaft 12 of the table. 150

As shown in Figs. 1, 2, and 3, a belt 64 runs over a small pulley 65 on the shaft 62 of the motor and thence to and over a larger pulley 66 on a shaft 67, which latter is located in a compartment of the box-like base of the casing heretofore described, see particularly Fig. 3. Like the table shaft 12 and the cutter head shaft 49, the shaft 67 is formed at its opposite ends with cone-shaped bearing recesses 68 and 69 to receive the cone-shaped ends 70 and 71 of pintles 72 and 73 supported in the opposite side walls of the base of the casing. At its end distant from the pulley 66, the shaft 67 is formed with a worm 74 which meshes with a worm wheel 75 arranged on a right angularly disposed shaft 76. This shaft is likewise formed with cone-shaped bearing recesses 77 and 78 at its opposite ends to receive the cone-shaped ends of pintles 79 and 80, respectively, supported in the fore-and-aft walls of the base of the casing, as also clearly shown in Fig. 3.

The shaft 76 has at its forward end a worm 81 which meshes with a helical gear 82 mounted on the vertical shaft 12 which carries the rotating table 11. The helical gear 82 is splined to the shaft 12, as shown in Fig. 3, so that the shaft may be adjusted vertically, as hereinbefore described, without interference by the said helical gear. It will be noted that the sizes of the pulleys 65 and 66 and the various parts of the gearing are so proportioned that the rotation of the table 11 will be at the low speed desired, as for example, 1 R. P. M.

It will be seen that a machine for trimming slugs made in accordance with the invention, as herein shown and described, will carry out the objects of the invention as enumerated, besides possessing other advantages which will be apparent to those skilled in the art.

Having thus described my invention, what I claim is:

1. In a machine for trimming the printing faces of type slugs, the combination of a frame, two shaft bearings mounted in said frame in axially alined spaced relation and provided with conical bearing surfaces, a driving shaft formed at its ends with conical bearing surfaces mating with those of said bearings and rotatably supported thereby, a slug supporting table carried by and rotatable with said shaft, a plurality of slug holding devices carried by the table and adapted to present the slugs with their printing faces exposed, means for rotating said shaft continuously at low speed, a cutter rotatably mounted in said frame in position to act on the exposed printing faces of the slugs as they pass in succession through the zone of action of the cutter, and means for rotating the cutter continuously and at relatively high speed.

2. In a machine for trimming the printing faces of type slugs, the combination of a frame, two shaft bearings mounted in said frame in axially alined spaced relation and formed with conical ends constituting bearing surfaces, a driving shaft formed in its ends with conical cavities in which said conical ends of the bearings seat and thereby give rotatable support to the shaft, a slug supporting table carried by and movable with said shaft, a plurality of slug holding devices carried by the table and adapted to present the slugs with their printing faces exposed, means for rotating said shaft continuously at low speed, a cutter rotatably mounted in said frame in position to act on the exposed printing faces of the slugs as they

pass in succession through the zone of action of the cutter, and means for rotating the cutter continuously and at relatively high speed.

3. In a machine for trimming the printing faces of type bars or slugs, the combination of a frame, upper and lower shaft supporting pintles mounted in the frame and provided with cone-shaped bearing portions, a spring support for the lower pinte tending to urge the same upwardly, a vertical driving shaft formed in its opposite ends with cone-shaped bearing recesses receiving the cone-shaped bearing portions of the pintles and rotatably supported thereby, a table fixed to said shaft and provided with a flat horizontal slug supporting surface, a plurality of slug holding devices carried by the table at different points in its circumference and arranged to present the slugs upright with their printing faces exposed, means for rotating the shaft continuously at low speed, means for adjusting the upper pinte upwardly or downwardly to vary the vertical position of the table, a rotary face-cutter mounted to turn about a fixed vertical axis and overlying the rotary table at one side, and means for rotating the cutter continuously at high speed.

4. In a machine for trimming the printing faces of type bars or slugs, the combination of a suitable frame, a shaft supporting pinte mounted in said frame and adjustable axially, a second shaft supporting pinte also mounted in the frame and movable to a limited extent to and from the adjustable pinte, releasable means for holding the pinte against movement, a spring acting on said second pinte and tending when the same is released to urge the same toward the adjustable pinte, a shaft rotatably mounted between said pintles, a slug supporting table fixed to the shaft to be rotated therewith, means on the table for holding the printing slugs with their type faces exposed, means for rotating the shaft continuously at low speed, a cutter rotatably mounted on said frame and positioned to act on the exposed faces of the slugs, and means for rotating said cutter continuously at relatively high speed.

5. In a machine for trimming the printing faces of type slugs, the combination of a frame, a shaft bearing adjustably mounted therein, a second shaft bearing mounted in the frame and movable to a limited extent to and from the adjustable bearing, releasable locking means for holding the bearing against movement, a spring support for said second bearing tending to urge the same constantly toward the adjustable bearing when the movable bearing is released, a driving shaft rotatably supported between said bearings, a slug supporting table fixed to said shaft, a plurality of slug holding devices carried by the table at different points in its circumference and arranged to present the slugs with their printing faces exposed, means for rotating the shaft continuously at low speed, a rotary face-cutter mounted in said frame to rotate about a fixed axis and in position to act on the exposed printing faces of the slugs, and means for rotating said cutter continuously at high speed.

6. In a machine for trimming the printing faces of type slugs, the combination of a frame, a lower spring-supported shaft bearing mounted therein, an upper shaft bearing screw threaded in the frame and adapted when turned to move to and from the lower bearing, a shaft

rotatably supported between said bearings, a
slug supporting table carried by the shaft,
means on the table for supporting slugs with
their printing faces exposed, a cutter rotatably
5 mounted on the frame and positioned to act on
the exposed faces of the slugs, means for ro-
tating the shaft and table continuously at low
speed, means for rotating the cutter continu-
ously at high speed, a calibrated dial carried by
the screw threaded upper bearing, and a pointer
on the frame in connection with which said
dial is adapted to be read to determine the ad-
justed position of the table. 80
